ATTORNEY

UNITED STATES PATENT OFFICE

GEORGE M. WOLFE, OF CHANUTE, KANSAS

FEED-WATER HEATER

Application filed November 8, 1928. Serial No. 317,941.

My invention relates to pre-heaters and more particularly to devices of that character for utilizing the products of combustion from a boiler for pre-heating the feed water for the boiler, the principal objects of the invention being to adapt a pre-heater for receiving gases directly from the boiler flues, to bring the gases from boiler flues immediately into contact with feed water conduits, to divide the gas column for maximum contact of heated products of combustion with water carrying conduits, to retain the gases in contact with the walls of conduits, and to conduct the water in a tortuous course over a large number of tubes heated by the gases coming from the boiler.

In accomplishing these and other objects of the invention, I have provided improved details of structure, the preferred forms of which are illustrated in the accompanying drawings, wherein:

Fig. 1 is a perspective view of the smoke box and adjacent portions of a boiler and my improved feed water pre-heater mounted therein, part of the smoke box wall being broken away to better illustrate the preheater.

Fig. 2 is a longitudinal central vertical sectional view through the smoke box and pre-heater and adjacent portion of the boiler, illustrating particularly the relation of the gas passages and water conducting members to the boiler tubes and flue.

Fig. 3 is a vertical cross-section of the smoke box and pre-heater on the line 3—3, Fig. 2, and showing portions of a feed water inlet and outlet.

Fig. 4 is an enlarged detail perspective view of a gas baffling member for positioning in a smoke passage.

Fig. 5 is an enlarged detail perspective view of opposite end portions of a plate for controlling the flow of water through the pre-heater.

Referring in detail to the drawings:

1 designates generally a boiler including a smoke box 2 having an outlet 3 for products of combustion, a boiler flue sheet 4 and tubes 5 through which products of combustion pass toward the smoke box and outlet.

My device comprises a shell or drum 6 and

including a pair of spaced preferably circular sheets 7 and 8 and a cylindrical rim or wall 9 secured to the peripheries of the sheets and having a portion 10 extending beyond the rear sheet 8 to engage the flue sheet and provide a chamber 11 between the end of the boiler and the adjacent sheet 8 of the shell, for purposes presently described.

The sheets 7 and 8 are preferably provided with similar edge flanges 12 secured to the cylindrical wall by rivets 13 and in sealed relation with the wall so that water may be fed through the shell as presently described.

The shell is mounted concentrically with the boiler and smoke box by brackets such as 14 and 15, the bracket 14 preferably comprising a relatively long band portion 16 engaging the cylindrical wall of the shell and having legs 17 secured to the smoke box for supporting the shell while the brackets 15 are supported from the smoke box for stabilizing the shell, the several brackets being preferably welded to the cylindrical wall.

I provide for the passage of gases from the boiler tubes through the shell for heating water conducted through the shell, and preferably provide passages 18 comprising tubes mounted in aligned openings 19 of the shell sheets and preferably having their outer ends swaged over the edges of the sheet opening as at 20 and sealingly engaged therewith, whereby water passing through the shell in contact with the tubes will be prevented from leaking therefrom.

An inlet 21 is provided adjacent the lower portion of the shell, preferably in the cylindrical wall, and an outlet 22 in the upper portion of the shell preferably in the portion of the cylindrical wall on the same side of the vertical axis thereof as the inlet, whereby feed water may pass upwardly through the shell toward the outlet.

The gas-conducting tubes are preferably installed in horizontal series and selected tubes are substantially in alignment with the gas-conducting tubes of the boiler. Located between the several horizontal series of tubes are baffles 23 comprising plates having side edges sealingly engaged with the sheets of the shell and ends engaged with the cylin-

drical wall, and provided with ports 24 for passage of water upwardly through the plates. The baffles form chambers or compartments such as 25, 26 and 27 in which the tubes 18 extend.

5 The plates may be welded to the shell sheets and their ends may be provided with flanges 28 for riveting to the cylindrical wall, the ports being preferably provided at 10 opposite ends of adjacent plates and dividing the flange at the perforate end to form pairs of ears 29 for attachment to the cylindrical wall.

15 The water entering the shell from the inlet and passing over the lowest series of tubes will leave the lower compartment at the end opposite the inlet and pass over the second series of tubes to the opposite end of the second compartment and so upwardly through 20 the shell, the water thus coming into contact successively with each of the tubes to absorb heat conducted therethrough from the products of combustion.

25 The alignment of tubes in the shell with the boiler tubes facilitates cleaning of the same by ordinary methods and I provide removable plugs 30 in openings 31 for each compartment for access thereto for cleaning deposits made by the feed water on the baffle 30 plates and outer surfaces of the tubes.

35 Located in each of the tubes 18 is a heat-radiating fin 32 comprising a flat plate portion 33 and a similar plate-like portion 34 and extending in a plane angular to the portion 32, each portion having a width equal to the diameter of the tube and the member having a length equal to the length of the tube.

40 The portions of the member 32 are in conductive relation with the wall of the tube, and provide relatively large surfaces for contact by gases to absorb heat therefrom and transmit the heat to the tube for absorption by the water.

45 In using the invention the feed water entering the shell at the bottom passes over the tubes through which gas is conducted and comes into contact with all of the tubes, whereby it is pre-heated to a relatively high 50 degree.

55 The spacing of the shell from the flue sheet of the boiler provides for installing a larger number of smoke passages in the shell than the number of boiler tubes, the chamber 10 distributing gases to the tubes located in offset positions from the ends of the boiler tubes.

60 The shell is also preferably spaced from the end sheet to permit hot products of combustion to pass over the inner sheet 8 for heating the same, the sheet comprising a heat-absorbing element, and the indicated position and use thereof may increase the amount of heat taken from the gases and 65 transmitted to the water.

What I claim and desire to secure by Letters Patent is:

1. In combination with a boiler shell, a flue sheet forming separate steam and smoke chambers in one end of the shell, a drum including front and rear head sheets spaced to form a water chamber, and means extending from the rear head sheet to the flue sheet forming in conjunction with said flue sheet, a closed chamber in the smoke chamber between the drum and flue sheet, brackets fixedly supporting the drum within the smoke chamber, tubes extending through the boiler and flue sheet for delivering gases to said closed chamber, tubes extending through the drum and its head sheets for delivering gases from the closed chamber to the smoke chamber, and water conduits leading to and from the drum. 70

80 85 90 95 100 105 110 115 120 125 130

2. In combination with a boiler shell, a flue sheet at one end of the shell forming separate steam and smoke chambers, a drum fixedly mounted in said smoke chamber including spaced front and rear head sheets and an annular wall forming a water chamber with the annular wall extended rearwardly to space the drum from the flue sheet and form in conjunction with said flue sheet an expansion chamber, tubes extending through the boiler and flue sheet to communicate with the expansion chamber, tubes extending through the drum and its head sheets providing communication between the expansion chamber and smoke chamber, and water conduits leading to and from the drum.

In testimony whereof I affix my signature.
GEORGE M. WOLFE.
